UNITED STATES PATENT OFFICE.

CLYDE L. EATON, OF PORTLAND, OREGON, ASSIGNOR TO COSMETIQUE LABORATORIES OF AMERICA, OF PORTLAND, OREGON, A CORPORATION OF OREGON.

DESIGN FOR A JAR OR SIMILAR CONTAINER.

Application filed June 16, 1927. Serial No. 22,447. Term of patent 3½ years.

To all whom it may concern:

Be it known that I, CLYDE L. EATON, a citizen of the United States, residing at Portland, in the county of Multnomah and State of Oregon, have invented a new, original, and ornamental Design for a Jar or Similar Container, of which the following is a specification, reference being had to the accompanying drawing, forming part thereof.

The figure is a front side elevation of the container showing my new design.

I claim:

The ornamental design for a jar or similar container, substantially as shown.

CLYDE L. EATON.
